UNITED STATES PATENT OFFICE.

ALBERT R. THOMPSON, OF SAN JOSE, CALIFORNIA, ASSIGNOR TO ANDERSON-BARNGROVER MFG. CO., OF SAN JOSE, CALIFORNIA, A CORPORATION OF CALIFORNIA.

COOKER, COOLER, AND THE LIKE.

1,402,193.

Specification of Letters Patent. Patented Jan. 3, 1922.

Application filed April 28, 1921. Serial No. 465,319.

To all whom it may concern:

Be it known that I, ALBERT R. THOMPSON, a citizen of the United States, residing at San Jose, in the county of Santa Clara and State of California, have invented certain new and useful Improvements in Cookers, Coolers, and the like, of which the following is a specification.

My invention relates to that class of machines and apparatus used in the canning art, in which the canned goods while undergoing treatment are carried through a receptacle in a definite path along a track composed of a fixed helically directed rail lying near the inner circumference of the shell, and a reel within the fixed rail and rotating about the axis thereof, said reel carrying a peripheral series of rails parallel with its axis and coacting with the fixed rail to support the cans and effect their travel in a helical path from their point of entrance into the receptacle to their point of discharge therefrom. Examples of these machines are those known as "cookers" in which the canned goods are heat-treated; and those called "coolers" in which the previously cooked canned goods are subjected to a lower temperature to cool them.

In these machines, accepted constructive practice, in respect to the reel member of the can-track, is to provide a single shaft constituting the driving axis of the reel, said shaft extending the full length of the reel and mounted in the receptacle ends. As such machines are usually quite long and the reels occupy substantially the entire length of the receptacle interior, it has been found somewhat difficult to arrange braces which will give the reel sufficient rigidity, chiefly because the long, through axis shaft presents an obstruction to effective bracing members.

One object of my present invention is to provide an efficiently rigid reel member of a can-track of the type mentioned, as will be hereinafter fully described.

Furthermore, in machines of this type the common practice has been to carry the fixed helically directed rail-member of the can-track, upon a series of longitudinal stringers supported in the receptacle and spaced from its wall. I have found, however, that a simpler construction is to bolt or rivet said rail member directly to and against the wall of the receptacle in which case said receptacle must of course be of circular cross sec-

tion. But this presents a difficulty of draining the receptacle of the treating liquid namely the water used therein; because a portion of the water will remain in the bottom between the coils of the helical rail if bolted directly against the receptacle wall, and will not drain out. Also, especially in the case of cookers, which require the inclusion within the receptacle of a steam-pipe for heating the water, the disposition of the helical rail directly against the receptacle wall, leaves no room for the steam pipe, which must, necessarily, be outside of the sphere of rotation of the reel member of the can-track. 70

Another object of my invention is to provide means by which the receptacle in which the fixed rail is disposed directly against its wall, may be fully drained and may also have a space or chamber for the inclusion 75 of a steam pipe.

With these ends in view my invention consists in the novel cooker, cooler, or like machine for treating canned goods, which I shall now fully describe by reference to the 80 accompanying drawings in which—

Fig. 1 is a longitudinal, broken, section, partly in elevation, of my improved machine or apparatus.

Fig. 2 is a cross section of the same on the 85 line 2—2 of Fig. 1.

1 is the receptacle of the machine, circular in cross section, except at the bottom, as will be presently mentioned. The receptacle is provided with an inlet indicated at 9 in 90 Fig. 1, and an exit, indicated at 3, for the canned goods which pass through it.

Within the receptacle and bolted or riveted directly to and against its wall is the fixed rail 4. This rail, which is preferably of T-section with its leg portion extending inwardly is helically directed throughout substantially the length of the receptacle, and forms one member of the can-track. The other member of said track comprises an annular series of spaced rails 5, preferably of angle section, lying and revolving within the fixed helical rail 4, in such relation thereto that the cans are carried and supported between the rail 4 and rails 5, the latter being 100 parallel to their axis of rotation, whereby the can path is a helical one throughout the length of the receptacle, all as is now well known and common in practice. The rails 5 form the periphery of a reel which in my 110

present improved construction comprises cross plates 6, short shafts 7, strut braces 8 and torsion braces 9. The short shafts 7 are fixed in the hubs 6' of the end plates 6 and said shafts are journaled for rotation in suitable bearings 10 in the ends of the receptacle 1. As illustrative of means for driving the reel, I show a worm gear 11 on one of the short shafts 7 and a worm shaft 12 engaging 10 said gear.

It will now be seen that by having the short-shafts 7, which thus leaves the cross-sectional areas of the reel free of obstructions, the strut braces 8 may be run diagonally for their full length directly through 15 said areas, thus stiffening the reel effectively. These braces are adjustably fitted at their ends in threaded nipples 8" carried by the plates 6, and they extend between adjacent 20 plates crossing in the axis region of the reel. To resist the torsional strain on the reel, I bolt to the reel-rails 5, between the plates 6, the diagonal torsion braces 9.

The bottom of the receptacle 1 is formed 25 with a longitudinally extending communicating chamber 13 of any suitable shape in cross section. A practical way of making this chamber is to distort the receptacle walls from the circular to a downward 30 convergence as shown in Fig. 2, thus giving it a V-shape. This chamber opens directly 35 into the interior of the receptacle, and the coils of the helically directed rail 4 span its width over its top. The ends of this chamber 13 are closed, but into one end 40 is fitted an inlet water pipe 14, and in its other end is a drain 15, adapted to be closed by a suitable removable plug—Fig. 1. It will now be seen that, notwithstanding 45 the disposition of the fixed helical rail 4 directly against the receptacle wall, all the treating water within the receptacle may be drained out as occasion requires.

In the case of a cooker, where a source of 50 heat must be provided, the bottom chamber 13, being outside of the fixed rail 4, serves as a means for introducing and housing a steam pipe 16.

In this connection it should be noted, 55 however, that in its mere function as a housing for a steam pipe, the outlying chamber is not necessarily at the bottom of the receptacle. It may lie along outside of any portion of the circumference of 60 said receptacle and be of advantage as such steam-pipe housing in connection with the primary feature of securing the helical rail directly against the inner surface of the receptacle wall.

60 I claim:—

1. A machine for treating canned-goods, comprising a receptacle having a can inlet and a can exit; a fixed helically directed rail disposed within said receptacle, and 65 forming one member of a can-track through

which the cans are advanced from the inlet to the exit; an annular series of spaced rails within the fixed helically directed rail, parallel with its axis, and forming the other member of said can-track; spaced cross 70 plates carrying said annular series of rails; short shafts mounted for rotation, one in each end of the receptacle, said shafts projecting into the receptacle and fixed in the end cross plates; and diagonal strut braces 75 crossing in the axial region of the annular series of spaced rails and extending their full length directly between and fitted to adjacent cross plates.

2. A machine for treating canned-goods, comprising a receptacle having a can inlet and a can exit; a fixed helically directed rail disposed within said receptacle, and forming one member of a can-track through 80 which the cans are advanced from the inlet to the exit; an annular series of spaced rails within the fixed helically directed rail, parallel with its axis, and forming the other member of said can-track; spaced cross plates carrying said annular series of rails; 85 short shafts mounted for rotation, one in each end of the receptacle, said shafts projecting into the receptacle and fixed in the end cross plates; diagonal strut braces crossing in the axial region of the annular 90 series of spaced rails and extending their full length directly between and fitted to adjacent cross plates, and diagonal torsion-braces secured to said spaced rails between 95 the cross plates. 100

3. A machine for treating canned goods comprising a receptacle, circular in cross section and having a can inlet and a can exit, said receptacle having an underlying longitudinal chamber opening into it; a 105 drain from one end of said chamber; a fixed helically directed rail secured to the receptacle wall and lying against the inner surface thereof, said rail spanning the communication between the receptacle and its 110 underlying chamber, and forming one member of a can-track through which the cans are advanced through the receptacle; and a rotatable annular series of spaced rails within the fixed helically directed rail, parallel with its axis and forming the other 115 member of said can track.

4. A machine for treating canned goods comprising a receptacle, circular in cross section and having a can inlet and a can 120 exit, said receptacle having an underlying longitudinal chamber opening into it; a drain from one end of said chamber; a fixed helically directed rail secured to the receptacle wall and lying against the inner surface thereof, said rail spanning the communication between the receptacle and its 125 underlying chamber, and forming one member of a can-track through which the cans are advanced through the receptacle; a ro. 130

- tatable annular series of spaced rails within the fixed helically directed rail, parallel with its axis and forming the other member of said can track, and a steam pipe housed 5 within said underlying chamber.
5. A machine for treating canned goods comprising a receptacle, circular in cross section and having a can inlet and a can exit, said receptacle having a longitudinal 10 chamber outside of its wall and opening into it; a fixed helically directed rail secured to the receptacle wall and lying
- against the inner surface thereof, said rail forming one member of a can-track through which the cans are advanced through the 15 receptacle; a rotatable annular series of spaced rails within the fixed helically directed rail, parallel with its axis and forming the other member of said can-track; and a steam pipe housed within said outside 20 chamber.

In testimony whereof I have signed my name to this specification.

ALBERT R. THOMPSON.
